CLAIM

The ornamental design for a shoe as shown and described.

DESCRIPTION

FIG. 1 is a bottom view of a shoe showing our new design;
FIG. 2 is a bottom rear perspective view thereof;
FIG. 3 is a bottom opposite side rear perspective view
thereof;

FIG. 4 is a bottom front perspective view thereof;
FIG. 5 is a bottom opposite side front perspective view
thereof;

FIG. 6 is a front view thereof; and,

FIG. 7 is a rear view thereof.

The broken line immediately adjacent to the top of the front photographic area defines a bound of the claimed design and forms no part thereof. The broken lines depicting the remainder of the shoe form no part of the claimed design.

1 Claim, 7 Drawing Sheets
